(57) **CLAIM**

The ornamental design for a small hand-held bag cutting device, as shown and described.

DESCRIPTION

FIG. 1 is a perspective view of the small hand-held bag cutting device.

FIG. 2 is a top plan view of the small hand-held bag cutting device.

FIG. 3 is a front side view of the small hand-held bag cutting device.

FIG. 4 is a left side view of the small hand-held bag cutting device.

FIG. 5 is a rear side view of the small hand-held bag cutting device.

FIG. 6 is a right side view of the small hand-held bag cutting device; and,

FIG. 7 is a bottom plan view of the small hand-held bag cutting device.

The small hand-held bag cutting device is made of semi-transparent material, is overall smooth in its surface, and has no decoration.
